UNITED STATES PATENT OFFICE.

THEODORE F. SCHIRMER, OF DAYTON, OHIO, ASSIGNOR TO THE STANDARD REGISTER COMPANY, OF DAYTON, OHIO, A CORPORATION OF OHIO.

AUTOGRAPHIC REGISTER.

1,150,890.

Specification of Letters Patent. Patented Aug. 24, 1915.

Application filed November 2, 1914. Serial No. 869,730.

To all whom it may concern:

Be it known that I, THEODORE F. SCHIRMER, a citizen of the United States, and a resident of the city of Dayton, in the county of Montgomery and State of Ohio, have invented certain new and useful Improvements in Autographic Registers, of which the following is a full, clear, and exact description, reference being had to the accompanying drawings, forming part of this specification.

The invention has relation to autographic registers of the "pull out" type, the principal features of which are a means for sup-
15 plying several webs of paper to a tablet plate upon which writing is to be done, a tension device at the end of the tablet to hold the paper firm while writing on it and while pulling it out over the tablet, and a
20 tearing blade adapted to form an edge against which the pulled out papers may be torn off.

In registers of such type, it is customary in the art to provide some means of locking
25 both the tension plate and tearing blade out of operative position in contact with the body of the device, so that the webs of paper can be threaded under the tension plate for restocking the machine.

30 The object of my invention is to provide, in a simple and inexpensive way, such a locking means, and it is accomplished by that certain structure and arrangement of parts to be hereinafter specifically pointed
35 out and claimed.

In the drawings, Figure 1 is a side elevation of the front portion of an autographic register, showing the tearing blade in contact position. Fig. 2 is a top plan view of
40 the same, with the blade broken away at one end to show the tension plate. Fig. 3 is a side elevation of the blade and tension plate on a larger scale with parts broken away, showing the blade raised from tearing position, and the tension plate raised out of contact with the tablet plate, and both locked in such positions. Fig. 4 is an end elevation
45 of the register taken at the "pull out" end, with the parts raised and locked.

50 The register shown has a casing 1, in which provision is made in any desired manner for the rolls of paper 2. The paper is brought up over the tablet plate 3 at the top of the casing, and when in use strips

of manifolding material are placed between 55 the two webs to make the duplicate copies.

At the "pull out" end of the register, that is to say, the end over which the webs of paper are drawn after entries have been made thereon, is located the tearing blade 4 60 and tension plate 5.

The tearing blade is mounted on a pair of arms 6 at each side of the casing 1, and these arms are rigidly mounted on the spindle 7, which extends across and is journaled in 65 the sides of the machine. By means of the spring 8, coiled around the spindle 7 and secured at one end thereto and secured at 9 to the casing, the spindle and hence the arms are under tension and tend to press the 70 blade 4 down against the end of the tablet plate.

The tension plate 5 extends across the machine underneath the tearing blade and has small spindles 10, 10 at each end. These 75 spindles are mounted in the slotted lugs 11, 11, formed in the casing of the machine, so as to permit of sufficient movement of the plate, and the plate is normally sprung pulled against the tablet plate end by means 80 of the ears 12, 12, extending through the tablet plate and secured by springs 13, 13, to the casing.

The arms 6, 6, of the tearing blade are mounted on the spindle 7 so as to leave a 85 space between them and the casing of the machine. Pivotaly mounted on the casing at 14 is a cam plate 15, which has space enough to swing between the blade arms and the casing. The top edge of the cam is so 90 disposed that it lies in contact with the spindle 10 (Fig. 3) of the tension blade, and the cam surface is such that when the cam is rocked by its handle 16, it will lift the spindle against its spring tension at 13, 95 and thereby lift one end of the tension blade and release the tension.

The handle 16 on the cam plate is so located that when the plate has been shifted to lift the spindle 10, the handle will lie 100 under the extended portion 6^a of the raised tearing blade arm. In order to shift the cam plate, however, the tearing blade must first be lifted, or the handle 16 will abut against the arm 6. When the tearing blade 105 is lifted on the other hand, the cam plate may be pushed over so that the handle 16 lies under the extension 6^a, whereupon the

spring tension on the tearing blade will hold over the cam, thereby maintaining the parts in locked open position.

The tearing blade arm has a handle 6^b by 5 which it is lifted, as must be done in each operation of the machine. When it is desired to stock the machine with paper, the webs from the rolls 2, 2, are brought up over the tablet plate, the tension plate and 10 tearing blade are locked up, as just described, and the webs fed under the tension plate. The tearing blade is then raised slightly, the cam plate handle released thereby, so that the cam can be swung back, and 15 the tearing blade allowed to return to tearing position against the tablet plate. Such notation as is desired is made on the exposed paper, the tearing blade raised slightly so that the end of the paper can be 20 reached, and the portion desired pulled out over the tablet while still under tension. The blade is then allowed to descend and the paper torn off at its edge.

It will be noted that the tearing blade 25 may be swung back as far as desired without affecting the tension plate in any way.

In devices where the tearing blade raises the tension plate, either the tension is constantly being released at the wrong time or 30 else there must be provided some kind of a lock to prevent the blade from being raised normally beyond a certain point. The spring tension on tearing blades in such machines has to be considerable and it is not 35 desirable to open the operator to the risk of having it shut down on his fingers when filling the machine. The device now shown is particularly free from this danger, as the tearing blade must be moved positively and 40 thus come under control of the operator, before the cam can be released to lower the tension plate.

It is not desired to be limited in the 45 claims that follow to such details of construction now particularly pointed out, as the mechanical equivalent thereof would as well fit the reading of the claims. It is believed that the structure is now fully and clearly specified, and that the principal object in providing for independent control of 50 tension plate and tearing blade in connection with a locking means for both is now apparent.

Having thus described my invention, what

I claim as new and desire to secure by Letters Patent, is:—

1. In an autographic register having a tablet for supporting a paper supply, a tension device to hold the paper, and a tearing blade, means independent of the tearing blade for raising the tension device, and means on the raising means to hold the tearing blade out of operative position.

2. In an autographic register having a tablet for supporting a paper supply, a tension device to hold the paper, and a tearing blade, a cam plate independent of the tearing blade for raising the tension device, and means on the cam plate to hold the tearing blade out of operative position.

3. In an autographic register having a tearing blade, and a tension device, a means for raising the tearing blade, an independent means for raising the tension device, and means on the latter means lying in the path 75 of the former means, and positioned so that the tearing blade must first be raised, to allow the tension device to be raised, and so that the tearing blade cannot be lowered until the tension device is lowered, for the 80 purpose described.

4. In an autographic register having a tearing blade and a tension device, arms for raising the tearing blade, a pivoted plate independent of said arms for raising the tension device, a contact means on the pivoted plate positioned in the path of the tearing blade, arms to prevent movement of the plate from normal position without raising 85 of the arms out of the way, and to prevent returning of the arms while the plate is in raised position.

5. In an autographic register having a tearing blade and a tension device, arms for raising the tearing blade, a pivoted plate 95 independent of said arms for raising the tension device, and a handle on the pivoted plate positioned in the path of the tearing blade, arms to prevent movement of the plate from normal position without raising 100 of the arms out of the way, and to prevent returning of the arms while the plate is in raised position.

THEO. F. SCHIRMER.
